J. T. AUSTIN.
PNEUMATIC ELECTRIC CIRCUIT CLOSER.
APPLICATION FILED JULY 28, 1916.

UNITED STATES PATENT OFFICE.

JOHN T. AUSTIN, OF HARTFORD, CONNECTICUT, ASSIGNOR TO AUSTIN ORGAN COMPANY, OF HARTFORD, CONNECTICUT, A CORPORATION OF MAINE.

PNEUMATO-ELECTRIC CIRCUIT-CLOSER.

1,322,506.

Specification of Letters Patent.

Patented Nov. 25, 1919.

Application filed July 28, 1916. Serial No. 111,852.

To all whom it may concern:

Be it known that I, JOHN T. AUSTIN, a citizen of the United States, residing at Hartford, in the county of Hartford and 5 State of Connecticut, have invented certain new and useful Improvements in Pneumato-Electric Circuit-Closers, of which the following is a specification.

This invention relates to a pneumato-electric circuit closer. A circuit closer involving the invention is susceptible of advantageous use in connection with various kinds of instruments, an organ and a piano being merely two illustrations of several. The 10 mechanism is simple in construction and positive and effective in action.

In the drawings accompanying and forming part of the present specification I have shown in detail one convenient form of embodiment of the invention which will be set forth fully in the following description. I do not restrict myself to this disclosure; I may depart therefrom in several respects within the scope of the invention defined by 15 25 the claim following said description.

Referring to said drawings:

Figure 1 is a sectional side elevation of tracker mechanism involving the invention.

Fig. 2 is a detail section, the section being 30 on the line 2-2 of Fig. 1, looking in the direction of the arrow cutting the line.

Fig. 3 is a like view on the line 3-3 of Fig. 1, looking in the direction of the arrow which intersects the line.

Like characters refer to like parts 35 throughout the several views.

The structure comprises a plurality of fixed contacts, movable contacts co-operative with and normally free of the fixed contacts, 40 and pneumatic means involving a tracker, for causing the movement of the movable contacts against the companion contacts. Obviously said movable contacts may be operated in any desirable manner.

As represented the mechanism involves in 45 its make-up a suitable carrier as the chamber 2 made of any desired material such as wood. This box or chamber constitutes a vacuum box or chamber and the air can be 50 exhausted therefrom in any desirable manner as by the duct or pipe 3 connected with the rear wall thereof and also with a suitable exhauster (not shown). The box at the front has an opening 4 covered in an air- 55 tight manner by a tracker bar 5 having

suitable openings in it which when uncovered by the perforations of a music sheet 6 put the interior of the chamber or box 2 by way of said uncovered openings into communication with the atmosphere. These 60 openings in the present case are formed by the bores of nozzles 7 set into perforations in the tracker bar 5 and leading rearwardly therefrom. The music sheet is led for example from the roller 8 onto the roller 9 as 65 familiar in automatic instruments of various kinds and in fact other arts, for as will be obvious, I do not limit myself to the use of the structure in the field of music.

In the chamber or box 2 and extending 70 from side to side thereof is a suitable support as 10. Fitted against the forwardly extending base portion 11 of the support 10 which may be of wood, are the butts of 75 spring fingers as 12 held in place in any convenient manner as by the strip 13 fastened to the support 10 as by screws 14. This strip 13 in addition to acting as a securing element also constitutes a conductor, being in contact as will be clear with the bases of the 80 several spring fingers. These fingers 12 are comparatively light, preferably sufficient in fact so as to be operated upon by pressure which in the present instance is atmospheric. Co-operative with each finger is a contact as 85 15, each finger and contact being part of a branch circuit as will hereinafter more particularly appear. These fingers as will be clear act as convenient means for controlling the respective branch circuits. To 90 facilitate their operation the upper ends of the fingers are bowed back as at 16, the bowed portions or curved heads 16 being opposite the delivery ends of the respective nozzles 7. Normally the springs 12 by their 95 own resiliency are maintained in the full line positions shown in Fig. 1 at which point they are free of the co-operating contacts 15.

It will be assumed that an exhaust appliance is connected with the duct or pipe 3, that the fingers 12 are in their normal positions shown in full lines as noted, and that the music sheet 6 is traversing the tracker bar 5. It will be further supposed that a perforation in the tracker bar registers with the inlet end of the nozzle 7 shown in said Fig. 1. In this event atmospheric air enters the nozzle in question and is directed against the head 16 of the contact finger or circuit controlling member 12 shown thus flexing 110

said part 12 and moving it against the contact 15 to close the branch circuit of which they form a part.

- The necessary electrical energy to effect the action of a part to be operated may be obtained in any desirable manner, for instance as by the battery 17. From one pole of the battery 17 the wire 18 extends and is connected with one end of the contacting and attaching strip 13. The other pole of the battery is connected as by the wire 19 with the magnet 20, leaving the magnet and extending to the contact 15 on the left. Extending from the other contacts are branch wires 21 connected with the magnets 22 and also with the main wire 19. The magnets are of horse shoe type, and their armatures 23 are carried by levers 24 fulcrumed as at 25.
- It will be clear, therefore, that when one of the fingers 12 is operated by pressure in the manner already set forth to cause the same to engage its coöperating contact 15, the local circuit of which they are a part and which includes one of the magnets described, is closed to effect the consequent energization of its magnet and the attraction of its coöperating armature 23. The armatures 23 may be connected with pipe governing means in an organ, piano playing means

in a piano or with other instrumentalities in any type of machine in which the mechanism may be incorporated.

While the movable contacts or spring fingers 12 are in a chamber or casing containing a vacuum and are operated by atmospheric pressure, the invention, as will be clear is not limited in this particular, although the construction specifically described is of advantage.

What I claim is:

A pneumato-electric circuit closer comprising a box, a tracker fastened to the box, having holes and also having nozzles extending inwardly from the holes, a series of 45 spring fingers, constituting contacts, corresponding with said holes, the fingers being mounted to yieldingly swing and their free ends being opposite the holes of the respective nozzles, and fixed contacts to be engaged 50 by the fingers when respectively forced thereagainst by air passing through the holes of the tracker and the nozzles.

In testimony whereof I affix my signature in the presence of two witnesses.

JOHN T. AUSTIN.
